UNITED STATES PATENT OFFICE.

ANDREW J. COLLIER AND PHILIP M. MAY, OF WASHINGTON, DISTRICT OF COLUMBIA; SAID MAY ASSIGNOR OF HIS ENTIRE RIGHT AND SAID COLLIER ASSIGNOR OF ONE-THIRD OF HIS RIGHT, BY DIRECT AND MESNE ASSIGNMENTS, TO GEORGE P. DAVIS, OF SAME PLACE, AND WILLIAM B. DICKEY, OF NEW ORLEANS, LOUISIANA.

CAR-FENDER.

SPECIFICATION forming part of Letters Patent No. 539,169, dated May 14, 1895.

Application filed September 1, 1894. Serial No. 521,905. (No model.)

To all whom it may concern:

Be it known that we, ANDREW J. COLLIER and PHILIP M. MAY, of Washington, District of Columbia, have invented new and useful

5 Improvements in Car-Fenders, of which the following is a full and exact description, reference being had to the accompanying drawings, making part of this specification.

Our invention relates to that class of fenders in which a trip mechanism is employed to actuate the guard when said trip mechanism strikes or comes in contact with a body or other obstruction accidentally on the track.

Our invention consists first in the combination with the independently operating guards or planks acting conjointly to close the entire space in front of and between the wheels, of a trip mechanism for throwing the guards into action and to permit the same to drop upon 20 the track or road bed in direct contact therewith, whereby to prevent any part or portion of the body or other obstruction from getting under the edge of the guard and consequently to prevent wedging and the riding of the car 25 over the object.

It further consists in a novel construction and arrangement of guard planks and the manner of mounting the same whereby they shall move both outwardly and downwardly 30 with their edges to pass beyond the side guard planks when resting upon the track in position to remove an obstruction or body whereby to prevent the object or body from being injured by said guards or planks by being drawn 35 under the same.

It further consists in certain novel features in the construction and arrangement of parts all as hereinafter described.

In the accompanying drawings, Figure 1 is 40 a perspective view of the front portion of a car-truck, showing our improvements applied. Fig. 2 is a longitudinal section of the same; Fig. 3, a perspective view of a modification in the form of a guard-plank, also showing the 45 manner of mounting the same in its support.

The guard fender and devices for controlling the same as hereinafter described may be connected to any form of car in the present instance being shown applied to the plat-

form of a motor car in which A represents 50 the platform; B, the journal boxes; C, the wheels; D, the side guards, and O the plank which extends in front of and between the wheels.

Connected to the underside of the platform 55 at suitable points between the wheels are brackets G, provided with horizontally arranged openings h, extending through the same from end to end and from which brackets extend depending bearings h', h², the one 60 h', also extending from the upper face of the bracket to pass through the platform.

The bearing h², is slotted vertically either in one or both its sides and has mounted therein a sliding bolt h³. A rod h⁴, extends across 55 between the brackets G, and passes through openings in the bolts h³, or otherwise rigidly connected therewith the rod passing through the slot or slots in the bearing serving to hold the bolt from turning therein. 70

The bolt h³, is provided with an opening or perforation h⁵, extending through the same at right angles to the rod h⁴, and in the lower end of said bolt is formed an eye h⁶, from which depends a chain h⁷, hereinafter referred to. 75

The lower end of the bearing h', is closed and said bearing has mounted therein a spring K and the bolt K', which rests upon said spring and which bolt is provided at its upper 80 end with a head K², having a roughened face for adapting it to be actuated or pressed by the foot of the gripman or other operator. This bolt is also provided with a horizontal perforation or opening k, also hereinafter described. 85

A bracket or bearing L, is connected to the lower face of the platform at a point between the brackets G, and has mounted thereon an arm lever L'. This lever at one end has connected thereto a vertically arranged arm or foot piece L², which extends through and has its bearings in the platform. The opposite portion of this lever is forked or bifurcated and is connected to the rod h⁴, and through it connected to the bolt h³, and acts in such a manner that as the lever L', is depressed by the attendant the guards will be elevated and 95

held by the engagement of the rods N, hereinafter referred to with the perforation in said bolt until tripped by the mechanism which will now be described.

- 5 Upon each side of the platform near the front thereof are connected depending hangers or bearings M, in which is mounted a swinging trip mechanism or curtain M². This trip mechanism or curtain is made of any desired material either metal or wood and may if preferred or found desirable be made of wire gauze with its central portion formed or of such configuration as to permit the free operation of the same without engagement with or obstruction from the couplings or other operating parts of the car. The lower end of this trip mechanism or curtain is preferably weighted to act to nominally hold the curtain in a vertical line as hereinafter explained.
- 10 Connected to the upper end of this curtain are rods N, which extend rearwardly from the same with their free ends passing into and having bearings in the brackets G, and in position to engage the bolt h³, and bolt K', before referred to.
- 15 The guard planks as before stated are shown as connected to the present form of planks O, now in use on cars which extend from the side guard planks and diverging forwardly to and meeting at a point between the wheels.
- 20 Connected to the upper end of this curtain are rods N, which extend rearwardly from the same with their free ends passing into and having bearings in the brackets G, and in position to engage the bolt h³, and bolt K', before referred to.
- 25 The guard planks as before stated are shown as connected to the present form of planks O, now in use on cars which extend from the side guard planks and diverging forwardly to and meeting at a point between the wheels.

30 The improved form of guard plank as hereinafter shown consists of two plates or planks P, P', of any suitable material either wood or metal and are mounted in or connected to their supports O, in the following manner.

35 Connected rigidly or extending from the rear faces of the planks or plates are bolts P² of a suitable length to pass through the supports O, and which bolts are provided with 40 suitably screw threaded ends for receiving nuts to hold the guard planks P, P' in proper relation to the supports O.

45 The supports or planks O, are provided with inclined slots having wearing surfaces O', near each end and through which slots the bolts P², pass and are adapted to move freely.

50 The guard plank P', is made longer than the plank P, and is curved in form as shown at p, to extend around the end of the plank P, and the arrangement of slots and length of planks P and P', are such that when raised the outer ends p², p³, will be drawn inward within the edges of the side guard planks and when depressed or resting on the track 55 or road bed the outer edges will extend out beyond the side planks to carry or guide a body or other object beyond or out of reach of said side plank and to cause the inner ends to be brought closely together with the curved 60 end of the plank P', to rest and pass closely against and around the end of the plank P. The chains h⁷, are connected to the planks P, P', at points about centrally of the length thereof and through which chains and connecting devices before described the planks 65 are elevated and held.

The bolt K', as also the arm or lever L', with its operating arm or foot piece may either be arranged to be actuated at the front of the car by a motor man or extended backward to 70 be actuated by a gripman on the ordinary form of grip car or arranged for its ready operation in accordance with the construction of car to which the device is to be applied.

The faces of the guard planks P, P', may be 75 cushioned in any preferred manner to prevent injury to an obstructing body coming suddenly in contact therewith, and if found desirable the lower edges of the planks may be extended forward as shown in the modification Fig. 3.

The openings or perforations k, and h⁵, are located or arranged in the bolt K', and bolt h³, so that when the planks are elevated to a proper height above the road bed or track 85 and the foot piece or bolt K', depressed the weight of the curtain or trip will force the rods N, through said openings or perforations and consequently hold said planks elevated, the spring actuated bolt K', acting thereon to 90 hold the rod with sufficient grip or force to prevent its accidental withdrawal from engagement with the bolts suspending the guard planks.

The operation of the device is as follows: 95 As the car is propelled or travels over the road should any object or body accidentally fall or be thrown on the track the same will engage the curtain or trip causing said curtain to move or swing backward and the rod 100 N, to be drawn forward first releasing the bolt h³, and afterward the bolt K', permitting the guard planks to drop down directly upon the track or road bed, the bolt K' acting to prevent the curtain from swinging downward 105 until the device is reset.

It will be seen that the construction and arrangement of parts while permitting the elevation of the trip or curtain and the guard plank sufficiently above the track or road bed 110 to pass over all immovable obstruction or unevenness of road bed acts to close the entire space in front of and between the wheels and to rest closely on said track or road bed when in action, and that the device is adapted to 115 any form of car and is also adapted to be quickly applied or removed either in whole or part for repair or other purpose.

It will also be seen that the curtain being pivoted to swing no object can be wedged under the same to prevent its free movement to trip the guard planks.

It will also be seen that while the device is light and durable the same is inexpensive needing no attention on the part of the gripman or motor man except to reset the device after being automatically tripped to remove an obstruction.

Having now described our invention, what we claim as new, and desire to secure by Letters Patent, is—

1. In a car fender the guard planks sup-

ported independently of each other, independent suspending mechanism for each of said planks, and a releasing mechanism provided with a single trip mechanism, substantially as described, whereby both planks may be engaged and released simultaneously as set forth.

5 2. In a car fender, the combination of the guard planks supported independently of each other acting conjointly to close the entire space in front of and between the wheels, independent suspending mechanism for each of said planks and a releasing mechanism provided with a single trip mechanism, arranged in advance of the planks for automatically and simultaneously tripping both planks, substantially as set forth.

10 3. In a car fender, the combination of the independent guard planks mounted to move in vertical planes to close the space in front of and between the wheels, independent suspending mechanism for each of said planks, and a releasing mechanism provided with a single tip mechanism for actuating the releasing mechanism, substantially as set forth.

15 4. In a car fender the supports for the guard planks provided with the slots inclining toward the side rails, in combination with the

guard planks provided with the rearwardly extending bolts to connect the guard planks 30 with the said supports through the slots, substantially as and for the purpose set forth.

5 In a car fender the combination of the brackets or hangers, the bolts mounted therein, the fenders flexibly connected with the 35 bolts, a rocking arm or lever connected to the bolt for raising the fenders, a curtain or trip, a reciprocating rod actuated by the fender to automatically engage and release the bolt, and a spring actuated tension device for engaging 40 the rod substantially as and for the purpose set forth.

6. In a car fender the independently supported guard planks, the fixed supports therefor provided with the inclined slots, one plank 45 provided with the curved end, adapted to overlap the other plank substantially as and for the purpose set forth.

In testimony whereof we have hereunto set our hands this 20th day of August, A. D. 1894.

ANDREW J. COLLIER.
PHILIP M. MAY.
